WALL OR PARTITION

Charles Edward Johnson, Chicago, Ill., assignor
to The Vitrolite Company, a corporation of
West Virginia

Application February 13, 1932. Serial No. 592,674

5 Claims. (Cl. 72—16)

The present invention has for its object to produce a simple and novel sanitary wall or partition projecting outwardly from and supported entirely by a wall in a building, or other wall; 5 whereby there will be no obstruction either below or above the projecting wall or partition.

My invention is particularly applicable for use as partitions for toilet booths or other compartments as they leave the floor underneath the same 10 entirely unobstructed.

In carrying out my invention, I employ a core in the form of a rugged framework which projects outwardly from the supporting wall in the manner of a cantilever, being suitably connected to 15 the supporting wall and suitably braced to hold it rigidly in place. The broad vertical faces of the core are then covered with a suitable sanitary sheathing and a heavy stile of opaque structural glass or other vitreous material is fastened over 20 the front edge of the core; the stile being heavy and strong enough to permit a door to be hung therefrom by suitable hinges. The sheathing on the broad faces is preferably in the form of suitable backing sheets or panels to which are cemented sheets or thin slabs of opaque structural 25 glass or similar material.

The various features of novelty whereby my invention is characterized will hereinafter be pointed out with particularity in the claims; but, 30 for a full understanding of my invention and of its objects and advantages, reference may be had to the following detailed description taken in connection with the accompanying drawings, where- 35 in:

Figure 1 is an elevation of a wall of a room equipped to receive my improved walls or partitions, the floor and ceiling being shown in section; Fig. 2 is a front elevation of a series of booths or compartments supported from the wall shown 40 in Fig. 1, a fragment of the supporting wall being shown, and the floor appearing in section; Fig. 3 is a section on line 3—3 of Fig. 2, showing also the ceiling which appears in Fig. 1; Fig. 4 is a section, on a larger scale, on line 4—4 of Fig. 3, 45 showing a fragment of the supporting wall and one of my improved partitions; Fig. 5 is a section on line 5—5 of Fig. 4; Fig. 6 is a view similar to Fig. 5, on a much larger scale, showing only fragments of the upper portion of the partition 50 and fragments of the support elements in the main wall that do not appear in Fig. 5; Fig. 7 is a section on line 7—7 of Fig. 4, on the same scale as Fig. 6; and Fig. 8 is a perspective view of one of the stile-supports.

In putting up a building, or in preparing a building already completed, the walls along which booths or compartments are to be located are properly equipped to support the partitions or panels that form the side walls of the booths 55 or compartments. Thus, as shown in Fig. 1, where

the booths or compartments are to be along the wall A, upright beams 1, 1 are mounted in the wall in spaced relation to each other, the beams extending from the floor B to the ceiling C. A comparatively heavy horizontal beam 2 extends 65 across and is secured to the beams 1, 1 at about the height to which the tops of the booths or compartments come. The partition walls are then hung from this cross beam which is braced at each such partition wall by a strut extending 70 down from the same to the floor; one of these struts being indicated at 3 in Figs. 5 and 6.

The partition walls, which constitute cantilevers when mounted on the supporting wall, are composed of metal cores suitably sheathed. 75 In the arrangement shown, each core is in the form of a hollow open-work structure of the desired vertical height or depth, the desired length from front to rear end comparatively thin or narrow. The framework illustrated is 80 composed of two square or rectangular side frames each formed of horizontal top and bottom members 4 and 5 and two upright members 6 and 7, connected together and braced at the corners by means of gusset plates 8. Each of these 85 frames is braced by diagonals 9 and 10 each extending between and connected at its ends to two of the gusset plates in diagonally opposite corners. The members 4, 5 and 7 may be angle 90 irons, whereas the front upright 6 is preferably a channel iron which serves as the front upright element of both of the frames. I prefer to thicken the partition wall toward the rear end, or at which may be termed the base, so that it will 95 have a wide bearing surface and be held to the supporting wall in such a manner that it cannot rock or sway laterally. At the rear the two side frames are connected together at the top and bottom by means of short angle irons 11 and 12. Extending over the top and bottom of the 100 open framework of the core are cover plates 13 and 14. The length of the cover plates is equal to the breadth of the frame from front to rear. The width of the top cover plate is the same 105 at various points along its length as the corresponding width of the core. The bottom cover plate, however, is much wider than the thickness of the core so that it projects laterally beyond each side of the core as shown in Fig. 7. The core is secured to the strut 3, conveniently by 110 bolts 15, 15 passing through the inwardly-directed flanges of the uprights 7, through the plate or strut 3 and through the web of the cross beam 2 which is in the form of a channel iron. Similar bolts may pass through the angle irons 115 7 and the strut or plate 3 at various points below the beam 2.

The cores are completed in the shop or factory, and, after they have been mounted in the positions which they are finally to occupy, they are 120

suitably sheathed with an attractive sanitary material.

It will be seen that the height of the core members is much less than the distance of the beam 2 from the floor so that, when the core members are mounted on the supporting wall, they leave the space directly above the floor entirely free and clear. Consequently, it is an easy matter to keep the floor clean, as there are no obstructions to catch and harbor dirt and germs or to interfere with sweeping, mopping or scrubbing processes.

The broad sides of each core may be faced or sheathed in any suitable manner, preferably in a manner to make the partition walls as sanitary as may be. To this end I prefer to provide a facing of opaque structural glass cemented to a suitable backing which is in turn secured in any suitable way to the core. In the arrangement shown, I place on each side of the core a covering in the form of a piece of wall board 17, secured in any suitable way. As best shown in Fig. 7, these wall board panels rest on the bottom plate 14 and extend up past the top plate 13. Sheets or thin slabs 18 of opaque structural glass or the like are then applied over the wall boards, being secured thereto by a layer 19 of cement and resting on the bottom plate 14.

The front edge of each core must also be covered. This may conveniently be done by means of a stile which is rugged enough to permit a door to be hung therefrom; whereby the booths or compartments are closed at the front by means of doors supported wholly from the partition walls which are in turn wholly supported by one of the walls of the building in which the booths or compartments are located. In the arrangement shown, each stile consists of a thick slab 20 of opaque structural glass or the like extending from the top to the bottom of the core and having a width considerably greater than the width of the front edge or face of the core. This slab is held in place by two clamping members, one at the top and one at the bottom. The construction of these clamping members is best shown in Fig. 8. It will be seen that each clamping member consists of a trough 21 having midway between the ends a stem or shank 22 projecting therefrom in the plane of the bottom wall of the trough; the adjacent side wall of the trough being cut away for a distance equal to the width of this shank or stem. The width of the trough is slightly greater than the thickness of one of the stiles, so that the ends of the stiles may be set into the troughs of the clamps. Projecting into the trough from the bottom wall are a number of dowel pins 23 that enter holes 24 cut into the end edge faces of the stile. The shank or stem of the clamp is provided with a number of bolt holes 25. The stem of the upper clamp lies upon the top plate 13 and is secured thereto by bolts 26 passing through the bolt holes 25. Similarly, the shank or stem of the lower clamp underlies and is secured to the bottom plate 14. I prefer to place on the top and bottom edges of the stile and in the holes 24 in the stile a thin layer 27 of mastic compound. By this means each stile will be securely held and cannot wobble.

As shown in Fig. 2, the space between each stile and the next adjacent stile is spanned by a door 28 hung from one of the stiles by means of suitable hinges 29.

In order to make the operation of facing the cores after they have been mounted as simple as

possible, the wall board backing panels may be tied to the core by suitable wires. Thus, I have shown such wires 30 passing around the diagonal braces 9 and 10 and through the wall boards. A few ties will suffice, since the facings become very stiff and rigid after the vitreous covering is cemented thereto, and will remain in place when attached at a few points.

After the partitions have been completed, the supporting wall is plastered, as indicated at D, and the sanitary panels or tiles E are applied over the plaster, preferably by means of a layer F of cement interposed between the tiles and the plaster. Thus, the metal beams and struts in the wall A are covered and the bases of the partitions are, in effect, embedded in the supporting wall.

It will thus be seen that I have produced a simple, novel and rugged wall or partition that may easily be set up, that remains firmly anchored and presents smooth faces that can easily be cleaned, and that requires no supporting member either above or below the same outwardly from the supporting wall therefor.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In combination, a support, a comparatively thin member in the form of a cantilever of considerable vertical depth projecting from said support, facings secured to and covering the broad faces of said member, a stile lying in front of the front edge of said member, and clamping elements projecting from the top and bottom of said member into holding engagement with the upper and lower ends of said stile.

2. The combination with a wall of a room, of a cantilever structure in the form of a long, narrow framework of considerable vertical depth projecting from said wall at some distance above the floor of the room, and layers of facing material secured to and covering the broad faces of said framework and wholly supported thereby.

3. The combination with a wall of a room, of a comparatively thin member in the form of a cantilever of considerable vertical depth projecting from said wall at some distance above the floor of the room, backing panels secured to the broad faces of said member, and vitreous facing material covering and cemented to said backing panels.

4. The combination with a wall of a room, of a comparatively thin member in the form of a cantilever of considerable vertical depth projecting from said wall at some distance above the floor of the room, backing panels secured to the broad faces of said member, vitreous facing material covering and cemented to said backing panels, a stile lying in front of the front edge of said member, and means securing the stile to said member.

5. The combination with a wall of a room, of a cantilever structure in the form of a long narrow framework of considerable vertical depth, projecting from said wall at some distance above the floor of the room, narrow ledges projecting from opposite sides of said structure at the bottom thereof, and facings covering the sides of said structure and resting on said ledges.

CHARLES E. JOHNSON.
